US0D1085552S

(12) **United States Design Patent** (10) **Patent No.:** **US D1,085,552 S**
(45) **Date of Patent:** **** Jul. 22, 2025**

(54) **ELECTRONIC EARMUFF**

(71) Applicant: **Shenzhen Jiajunxing Technology Co., Ltd.**, Shenzhen (CN)

(72) Inventors: **Hui Jiang**, Shenzhen (CN); **Honggang Wei**, Shenzhen (CN)

(73) Assignee: **Shenzhen Jiajunxing Technology Co., Ltd.**, Shenzhen (CN)

(**) Term: **15 Years**

(21) Appl. No.: **29/946,726**

(22) Filed: **Jun. 11, 2024**

(30) **Foreign Application Priority Data**

May 29, 2024 (EM) 015061945-0001

(51) **LOC (15) Cl.** **29-02**

(52) **U.S. Cl.**

USPC **D29/112**

(58) **Field of Classification Search**

(57) **CLAIM**

The ornamental design for an electronic earmuff, as shown and described.

DESCRIPTION

FIG. 1 is a left perspective view of an electronic earmuff showing our new design;

FIG. 2 is a right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depict the portions of the electronic earmuff that form no part of the claimed design.

1 Claim, 8 Drawing Sheets
